UNITED STATES PATENT OFFICE.

JOHN E. MILLER, OF OLEAN, NEW YORK.

CHAIN FASTENER.

Application filed February 18, 1922. Serial No. 537,522.

To all whom it may concern:

Be it known that I, JOHN E. MILLER, a citizen of the United States, residing at Olean, in the county of Cattaraugus and 5 State of New York, have invented new and useful Improvements in Chain Fasteners, of which the following is a specification.

My present invention has reference to a means for fastening the end links of a 10 chain.

My object is to produce a device of this character which shall be of an extremely simple construction, easily attached to the end links of a chain, and automatically 15 locked by an outward pull exerted by the chain.

A further object is to produce a means for locking the ends of chains that constitutes a body member formed of spaced 20 plates having hooked portions at one end thereof, a pintle member being slideable through the plates adjacent to the other end of the body and to which pintle one of the 25 end links of the chain is connected, while in the body there is pivotally secured a latch plate having a hook portion to cooperate with the hooks of the body to engage therebetween the opposite end link of the chain, said latch plate having a bayonet 30 slot designed to be moved over the pintle, and the said pintle being designed to be forced into the longitudinal passage of the 35 said slot when outward pressure is exerted upon the chain, while in addition to this, removable means may be provided for locking the latch on the body.

The foregoing objects, and others which will appear as the nature of the invention is better understood, may be accomplished 40 by a construction, combination and operative association of parts, such as is disclosed by the drawings which accompany and which form part of this specification.

In the drawings:

45 Figure 1 is a perspective view of the improvement showing a chain fastened thereon.

Figure 2 is a longitudinal sectional view on the line 2—2 of Figure 1.

50 Figure 3 is a sectional view on the line 3—3 of Figure 2.

Figure 4 is a plan view of the device as illustrated in Figure 1.

55 Figure 5 is a view showing the device in open position, parts being in section.

The body of my improvement comprises

two complementary plates 1—1. These plates are formed on one of their edges, adjacent one of their ends with enlargements that provide jaws 2. The plates, adjacent 60 the ends thereof opposite those formed with the jaws have somewhat elongated slots 3 therethrough, and through these aligning slots there is passed a pintle 4. The pintle has both of its ends headed and has secured 65 thereto one of the end links of a chain 5. Swingly secured between the body plates 1, through the medium of a pivot 6 is a latch plate 7. The latch plate has one of its edges widened and rounded to form the 70 same with a jaw 8, the bight of the jaw being rounded outwardly, and the edge of the plate on which the jaw is formed being rounded downwardly to the opening in the enlargement that forms the jaw. The jaw 75 8 is designed to cooperate with the jaws 2 of the body, it being noted that the pivot 6 passes through the end of the latch plate adjacent the jaw 6. The latch plate has its edge, opposite that formed with the jaw, 80 and adjacent the end of the said plate opposite the said jaw, formed with a bayonet slot 9, the said slot designed to receive therein the pintle 4, and when an outward pressure is exerted upon the chain 5 the 85 pintle will be moved outwardly on the body into the longitudinal passage of the bayonet slot, thus holding the latch plate in locked position on the body. The opposite end link of the chain 5 is received between 90 the jaws 2 and 8, and it will be apparent that with a construction as above described the ends of the chain may be easily, quickly and effectively connected.

To more effectively hold the latch plate 95 in locked position on the body, I provide the body plates 1 and the latch plate with aligning apertures through which may be passed a holding element such as a cotter pin 12.

100 It is thought that the foregoing description, when taken in connection with the drawings will fully set forth the construction and advantages of the improvement to those skilled in the art to which this invention relates and that further detailed description will not be required.

While I have illustrated the body of the improvement as constructed of two plates 1—1, it is to be understood that the outer 105 member or casing of the improvement may be formed from a single strip of suitable

material bent and shaped to provide spaced members, similar to the plates 1—1.

Having described the invention, I claim:—

In a device for the purpose set forth, a body comprising spaced plates having one of their edges adjacent one of their ends formed with similar jaws, a latch plate arranged between the body plates and pivoted thereto at the jaw end of the body, said latch plate having one of its edges adjacent its pivoted end formed with a rounded jaw to cooperate with the jaws of the body and to receive the link of a chain therebetween, said body plates having an aligning elongated slot, a pintle passing therethrough to which the second end link of the chain is connected, said latch plate having a bayonet slot designed to receive therein the pintle and whereby an outward pressure on the chain will cause the pintle to move into the longitudinal passage of the said bayonet slot, and removable means passing through the body and latch plate for locking the latch plate to the body.

In testimony whereof I affix my signature.

JOHN E. MILLER.
